G. F. & C. I. WILSON.
IRONING BOARD.
APPLICATION FILED OCT. 22, 1908.

923,097.

Patented May 25, 1909.

UNITED STATES PATENT OFFICE.

GEORGE F. WILSON AND CHARLES I. WILSON, OF SAVANNAH, MISSOURI.

IRONING-BOARD.

No. 923,097.

Specification of Letters Patent.

Patented May 25, 1909.

Application filed October 22, 1908. Serial No. 459,002.

To all whom it may concern:

Be it known that we, GEORGE F. WILSON and CHARLES I. WILSON, citizens of the United States, residing at Savannah, in the county of Andrew and State of Missouri, have invented certain new and useful Improvements in Ironing-Boards; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention pertains to a new and useful ironing board and the invention in its fundamental principles has for its object to provide a device of this character which is simple and efficient in construction and exceedingly practical in the application.

A further object of the invention is to provide a device of this design, whereby it may be easily and effectively attached to a table, as shown clearly in the accompanying drawings.

A further object is to provide a new and novel supporting leg for the ironing board and which, when manipulated, actuates a new and novel locking member between which and the said ironing board the table is firmly clamped, as will be clearly manifest.

The invention comprises various details of construction, combinations and arrangements of parts which will be hereinafter more fully described, shown in the accompanying drawings and the novel features thereof will be pointed out in the appended claim.

To obtain a full and correct understanding of the details of construction, combination of features, elements and advantages, reference is to be had to the hereinafter set forth description and the accompanying drawings in connection therewith, wherein:—

Figure 1 is a perspective view of a portion of a table, showing the improved ironing board applied thereto. Fig. 2 is a side elevation of a portion of a table also showing the ironing board applied thereto and clearly illustrating the manner in which the ironing board is clamped or locked to the table. Fig. 3 is a bottom plan view of the ironing board showing the locking member and the leg supporting member lying adjacent the under face of the ironing board. Fig. 4 is a detail per-

spective view of hinged connections, showing part of the invention.

In regard to the accompanying drawings, wherein similar reference characters indicate corresponding parts in the several illustrations, by numerals, 1 designates a suitable table, to which the ironing board 2 is applied, as clearly shown in Figs. 1 and 2 of the drawings. Fixed to the under face of the ironing board are hinges 3 between the portions 4 of which a clamping member 5 is pivoted upon the pin 6, as shown clearly in Figs. 2 and 3 of the drawings. Between the end 7 of the clamping member 5 and the end 8 of the ironing board, the table 1 is clamped, as will be observed upon referring to Figs. 1 and 2. The end 10 of the clamping member is provided with a reduced portion 11, which is pivoted between the arms 12 of a bifurcated portion 13 of a leg supporting member 14, as clearly shown in Figs. 2 and 3.

It will be seen, upon referring to Fig. 2 of the drawings, that the leg supporting member 14 is disposed in parallel relation to the legs of the table so as to cause the ends 13 of the arms 12 to have a cam action upon the under face of the ironing board so as to throw the end 7 of the locking member upward, thereby securely clamping the top of the table, as will be clearly evident upon referring to Figs. 1 and 2 of the drawings.

The leaf portions 4 of the hinges 3 are hinged to the plates 16, which together with the portions 4 compose the said hinges 3, which plates 16 are secured to the under face of the ironing board by suitable screws 17, as clearly shown in Fig. 3.

From the foregoing, it will be noted that a simple and novel ironing board is afforded and which may be easily and quickly applied to a table and having means whereby the table is securely clamped. It will be further noted that a new and novel leg supporting member is afforded, which, when manipulated for supporting the ironing board, actuates a locking member between which and the ironing board the table is clamped.

Having thus fully described our invention, what we claim to be new and desire to secure by Letters Patent is:

In combination with an ironing board, hinge plates fastened to the under surface thereof, parallel to each other and spaced apart, hinge leaves one hinged to each of said plates and having a contracted end, a clamp-

ing bar to which said contracted ends of the leaves are pivotally connected, a leg having pivotal connections with one end of said bar and adapted to frictionally bind against the under surface of the board to cause the opposite end of the bar to coöperate with the end of the board to hold the same upon the edge of a table, as set forth.

In testimony whereof we hereunto affix our signatures in the presence of two witnesses.

GEORGE F. WILSON.
CHARLES I. WILSON.

Witnesses:

O. J. HURLEY,
P. S. BOOKER.
